METHOD OF MANUFACTURING STOCKINGS

Emil Fischer, Bloomfield, N. J.

Application October 27, 1938, Serial No. 237,173

3 Claims. (Cl. 66—82)

My invention relates to the process of producing knitted stockings on flat knitting machines, and refers particularly to methods in which the stocking is knitted from the foot portion to the leg portion.

According to my process, the stocking may be knitted by commencing at the foot and at the same time knitting the heel portions on each side of the foot portion. The heel tabs may be started directly with the toe portion, or at any convenient time thereafter, as long as the heel tabs have the desired length when it is time to transfer them with the narrowing machine to their respective knitting needles in order to give a continuous knitting with the high heel. If the heel tabs are finished before the foot portion is knitted up to the instep portion, the narrowing combs will take the heel tabs off the knitting needles and hold them until the knitting has proceeded up to the instep portion and then the heel tabs are transferred to the knitting needles in order to give a continuous knitting with the high heel.

The advantages of knitting stockings according to my invention are as follows:

In knitting the heel tabs on each side of the foot portion while the foot is knitted is a saving of time, for it is not necessary to operate the machine for just producing the heel tabs, further, the jointure of the high heel and heel does not require a manual power and gives a perfect connection between the two, further, a so-called French heel is produced without interrupting the knitting in the instep portion, and further, my process can be followed out on a full fashioned knitting machine.

In the accompanying drawing illustrating the several steps incident to the following of my process similar parts are designated by similar numerals.

Figure 1 is a diagrammatic illustration of a stocking blank and heel tabs particularly adapted for the following of my process when the knitting operations are commenced at the toe portion of the stocking.

Figure 2 is a diagrammatic illustration of a stocking blank and heel tabs particularly adapted for the following of my process when the knitting operations are commenced at the heel tabs and toe portions of the stocking.

Figure 3 illustrates a stocking produced by my process after the seaming and looping operations.

The following is a general description of the method of my invention in which knitting com-

mences at the toe and heel portions as illustrated in Figure 2. The heel tabs will be knitted on each side of the toe. This will not interfere with the knitting of the toe. In order to get a good fashion and a good selvage in the toe at least four yarn carriers should be used, three carriers for body yarn which alternate every third course, and one carrier for reinforcing the toe. The three carriers for the body yarn are especially necessary for producing a good selvage.

One to two carriers in each heel tab may be used in knitting the heel portions, or one carrier with two tubes for two different yarns can be used in each heel. This is very helpful in producing a good selvage in the widening of the heel tabs.

After the toe and the heel tabs are finished, the heel tabs will be transferred to the narrowing combs and kept there until the knitting has proceeded up to the instep, then a loose course 12 in each sole is knitted, followed by two or three or more ravel-courses, the heel tabs are then transferred to their specific knitting needles in order to give a continuous knitting with the high heel.

The heel tabs can be knitted at any convenient time after the toe has been started as long as they have the desired length before arriving at the high heel 13.

In knitting the heel tabs on each side of the sole portion 14, as shown in Figure 1, and then having the desired length at the beginning of the high heel, it is only necessary to transfer them to their specific knitting needles in order to continue knitting, with the high heel. This is accomplished without having kept the heel tabs for any length of time on the narrowing combs, as is necessary if the heel tabs have the desired length and knitting has not yet proceeded up to the instep. After the high heel is knitted, the leg portion 15 is knitted.

The stocking can be finished in any desirable suitable manner.

It will thus be seen that my invention presents a process for knitting stockings on a full fashioned knitting machine in which the heel tabs are knitted on each side of the toe portion, then transferred to the narrowing combs and when the proper time arrives are transferred to the specific knitting needles, thus allowing a continuous knitting with the high heel portion; and that my process thus presents a rapid, simple and economic method for the knitting of stockings.

My invention is not limited to the specific de-

scription given herein, but is sufficiently extensive to include any modification thereof within the scope of my disclosures.

What I claim is:

1. A method of knitting stockings upon a full-fashioned knitting machine which comprises simultaneously knitting the toe portion and heel tabs at each side thereof, transferring said heel tabs to narrowing combs, continuing knitting foot portion to instep, transferring said heel tabs to knitting needles, adapted for knitting the high heel portion, continuing knitting said high heel portion and knitting the leg portion.

2. A method of knitting stockings upon a full-fashioned knitting machine which comprises simultaneously knitting the toe portion and heel tabs at each side thereof, transferring said heel tabs to narrowing combs, continuing

knitting foot portion to instep, knitting a loose course in each sole of the foot portion, adding a few courses, transferring said heel tabs to knitting needles adapted for knitting the high heel portion, continuing knitting said high heel portion and knitting the leg portion.

3. A method of knitting stockings upon a full-fashioned knitting machine which comprises simultaneously knitting the toe portion and heel tabs at each side thereof, transferring said heel tabs to narrowing combs, continuing knitting foot portion to instep portion, knitting a loose course in each sole portion, adding a few courses, transferring said heel tabs to knitting needles adapted for knitting the high heel portion, knitting the sole portion together with the heel tabs to the high heel portion, continuing knitting said high heel portion and knitting the leg portion.

EMIL FISCHER.
